6 Claims. (Cl. 174—121)

The present invention relates to new products, cables and similar articles, and a process for producing them.

It is known to produce cables consisting of an elementary core and an external envelope. The core yarns may be characterised by the absence of appreciable twist, these yarns being assembled with one another and with the external envelope surrounding them by means of an appropriate chemical binder. These ropes have a particularly high breaking strength with low elongation.

The present invention provides a cable comprising at least one substantially axial filiform metallic element surrounded by a composite structure consisting of textile yarns substantially parallel to the axial element and at least one external envelope united to the yarns, the filiform element possessing different dynamometric characteristics from the composite structure.

In a preferred cable, the axial element has an elongation at break, which is greater than that of the composite structure.

The nature of the cable may be varied to suit any particular use by appropriate choice of the constituent elements. It is possible to use stranded or unstranded electric conductors as the axial element. Such cables possess a distinctly lower weight than conventional electric cables, and they are consequently easier to handle. The nature of the composite element may be so chosen that the cables are insensitive to water, to weather influences and to cold, and have good resistance to external corrosive agents, while requiring no maintenance during service.

The axial element may also have a breaking load which is higher than the maximum working load tolerated by the composite structure. Any strong and non-inflammable material which conforms to this definition, such as steel rope, may be employed so that the cable will not suddenly break under load, for example in the event of accidental wear.

A preferred embodiment of the present invention will now be described with reference to the accompanying drawing in which the axial element has been labeled as a metal element. The axial element, when the cable is to be used as an electrical conductor, can comprise a metal wire coated with a suitable electrical insulation. The axial element is surrounded by a plurality of continuous filaments which are parallel to the axial element. The filaments are bonded together and the assembly is covered with a suitable envelope.

Any known method may be employed to produce such cables but the following method is preferred. The textile yarns are impregnated with a chemical binder, the axial element and the textile yarns are assembled continuously and at least one envelope is then applied while the binder is still in the adhesive state, the envelope being impregnated at least partially due to the exudation of the binder when it is united with the textile yarns.

In a preferred embodiment of the present invention, the textile yarns are introduced parallel to one another, in the form of a sheet, into a bath containing an appropriate chemical binder, together with an axial element which is optionally coated or sheathed. By means of a device, such as a perforated disc, the yarns are uniformly distributed in circular arrangement around the axial element, the binder is partially dried and the assembly is

2

thereafter united without twisting. An external envelope obtained, for example, by braiding is deposited on this assembly, optionally after re-impregnation. The braid is impregnated by the binder which exudes through it and this may be supplemented by continuous passage through a second binder bath which thus completes the protection of the assembly.

The textile yarns employed for the formation of these cables may be of natural, artificial or, preferably, synthetic origin, the latter types of yarns having the advantage of higher strength for a given weight. Such yarns are, notably, based on polyamide, polyester, polyolefine, polyacryl, polyvinyl, etc. Advantageously, yarns having very high strength and low elongation will be employed, which under these conditions retain their mechanical properties to the maximum extent.

The binders employed for the impregnation of the textile filaments may be of very varied nature: natural or synthetic elastomers, in the form of a latex or a solution, vinyl or other polymers, polycondensates, paraffins, waxes, etc., and they advantageously contain protecting and/or stabilising agents. Depending upon the nature of the binder, the latter may be deposited in solution, in dispersion or in a viscous liquid state.

Some binders, such as elastomers, may be self-curing or they may be subjected to curing after the cable has been formed. In order to render these cables incombustible and/or impetrucible, it is sufficient to incorporate fire-proofing and/or fungicidal products in the binder.

The external envelope may be obtained by lapping, taping, extrusion or, preferably, braiding and may be applied continuously. If desired, it may be externally coated with an abrasion-resistant resin, such as polyvinyl chloride, synthetic elastomers, polyamides, polytetrafluoroethylenes, etc.

In order that the technical features and the advantages of the present invention may be more readily understood, two embodiments thereof will be described by way of example.

Example I

170 high-tenacity polyethylene terephthalate yarns having a count of 1000 deniers/200 filaments, and a bare copper cord having a diameter of 3 mm. and composed of 7 elemental filaments having a diameter of 1 mm., are passed parallel to one another, in sheet form, through a binder consisting of a self-curing enriched rubber latex containing fungicides and curing ingredients. On leaving the tank, the yarns are carried vertically upwards, whereafter they are passed through a perforated disc which positions them in relation to one another, so that the axial element is located at the centre of the said disc. At the same time, drying of the binder is commenced.

The assembly, consisting of the yarns and the copper cord, is passed through a calibrating nozzle, the orifice of which has a diameter similar to the final diameter of the cord. The assembly thus shaped and still impregnated with fresh binder is passed along the axis of a braiding machine comprising 16 spindles each supplying 3 yarns of polyethylene terephthalate having a count of 1000 deniers/200 filaments.

The assembly is thereafter passed through a self-curing "Hypalon" solution charged with carbon black, and then through a resilient conical sleeve, of which the smallest diameter corresponds substantially to the diameter of the finished cable, the surface of the latter thus being smoothed.

The product is thereafter passed through a tunnel oven, of which the temperature varies between 50° and 130° C. and in which it remains for about 5 minutes, whereby drying of the binder and its curing are ensured.

Such a cable is designated A in the following table, a

cable formed solely by the composite structure is designated B and a bare copper cord is designated C.

Until rupture, the copper cord is not broken because its elongation is greater than that of the composite structure, but immediately rupture of this structure occurs it also breaks under the load.

	Diameter in mm.	Weight in g./m.	Breaking load in kg.	Elongation at break, percent
A	6.5	82	1,300	7
B	5.7	32	1,080	7
C	3	50	255	11

Example II

The same procedure is adopted as in Example I but the copper cord is replaced by a steel rope having the following characteristics:

Diameter in mm. 1.4
Weight in g./m. 12
Breaking load in kg. 205

This steel rope is surrounded by a textile complex formed of 100 elemental high-tenacity polyethylene terephthalate yarns, 1000 deniers/200 filaments, having a 20 S twist, and by a braided envelope obtained from 16 spindles fed with polyhexamethylene adipamide yarns, 840 deniers/3 filaments, having a 70 Z twist.

The cord obtained weighs 33 grams per metre and works under normal conditions with loads below 200 kg. If, in this zone of use, an accident occurs which results in breakage of the composite element, such as shearing, wear due to alternating forces, fire, etc., the steel rope supports the load momentarily and thus increases the safety of such cables in use.

This type of cable is also suitable for static uses, such as cables for avalanche barriers.

I claim:

1. A cable comprising at least one substantially axial filiform metallic element surrounded by a composite textile structure consisting of a bundle of organic continuous filament yarns substantially parallel to the axial metallic element and by at least one external braided envelope, said composite textile structure being impregnated by an organic bonding material, the axial metallic element having one dynamometric property selected from the group which consists of maximum working load and elongation at break greater than that of the remainder of the composite structure of the cable.
2. A cable according to claim 1 in which the axial metallic element is an electric conductor.
3. A cable according to claim 1, in which the axial metallic element is of copper and has an elongation at break greater than that of the remainder of the composite structure of the cable.
4. A cable according to claim 1 in which the axial metallic element is a load bearing element.
5. A cable according to claim 1 in which the axial metallic element is of steel and has a maximum working load greater than that of the remainder of the composite structure of the cable.
6. A cable according to claim 1 in which the bonding material is a cured elastomer.
